UNITED STATES PATENT OFFICE.

WARREN F. FARAGHER, OF PITTSBURGH, AND WILLIAM A. GRUSE, OF WILKINSBURG, PENNSYLVANIA, AND FREDERIC H. GARNER, OF FAWLEY, ENGLAND, ASSIGNEES TO GULF REFINING COMPANY, OF PITTSBURGH, PENNSYLVANIA, A CORPORATION OF TEXAS.

PROCESS AND APPARATUS FOR CRACKING HYDROCARBON OILS.

Original application filed January 15, 1921, Serial No. 437,481, and in Canada December 29, 1921. Divided and this application filed March 28, 1923. Serial No. 628,501.

This invention relates to an improved method and apparatus for making motor fuel or gasoline by cracking hydrocarbon oils, such as the higher boiling fractions and residual oils of petroleum or shale oil distillation. This is a division of our application Serial No. 437,481, filed January 15, 1921. More particularly, the invention relates to improvements in the cracking of oil in a horizontal cylindrical boiler type of still heated externally to the cracking temperature.

When such oils are subjected to cracking in an externally heated still, serious difficulties are encountered in large-scale operations, due to the deposition of a carbonaceous solid, commonly referred to as "carbon" on the heated walls of the still. Such a deposition of "carbon" interferes with the conduction of heat into the oil, and results in increased cost of gasoline-production owing to the necessity of cleaning the "carbon" from the still walls and the loss of operating time during such cleaning operations; while the life of the still wall is comparatively short due to the rapid burning out of the iron in contact with "carbon".

Attempts have been made to overcome the difficulties mentioned by providing stirrers in the still for agitating the oil, but such stirrers are open to the objection that they require stuffing boxes which must operate against highly heated oil or hot oil vapors at high pressures.

According to the present invention, the cracking operation is carried out in a horizontally arranged cylindrical still, such as is commonly used in cracking oils, but the cracking operation is carried out without objectionable "carbon" deposition and accumulation on the heated bottom of the still, and with avoidance or substantial avoidance of the objections above referred to.

In carrying out the improved cracking operation of the present invention, we provide a plurality of directing baffles longitudinally arranged in the still, and spaced apart to permit circulation of oil therebetween, and between the baffles and the still walls, and we maintain an effective circulation of the

oil in the still around the baffles and between the baffles and the heated still walls by the introduction of currents of gas between the baffles and the still walls so that the entire body of oil in the still is kept in continuous and effective circulation and heated to a substantially uniform temperature throughout, and so that objectionable "carbon" deposit on the heated bottom of the still will be prevented or removed by the circulating oil. The number of longitudinal baffles provided may vary in shape and arrangement, as well as in number, provided they permit effective circulation of the entire body of oil in the manner above described. This circulation takes place along both sides of the heated bottom of the still, in opposite directions, either toward or away from the central bottom portion of the still; that is, the oil is either circulated from the center of the still, at the bottom, upwardly along the sides of the still, in opposite directions, and back to the central portion of the still after passing between the outer baffles and the still walls, or the oil can be circulated downwardly between the baffles and the still walls, in opposite direction, to the center of the still at the bottom, and thence returned upwardly thru the central portion of the still for recirculation. The intermediate spaces between the baffles, thru which the oil has a downward flow are left open and unobstructed thruout their length.

The invention will be further illustrated and described in connection with the accompanying drawings, which show, in a somewhat conventional and diagrammatic manner apparatus embodying the invention, and adapted for the practice of the process of the invention.

In the accompanying drawings Fig. 1 shows a transverse vertical section of line 1—1 of Figure 2, Fig. 2 shows a longitudinal vertical section of line 2—2 of Figure 1 and Fig. 3 is a view similar to Fig. 1 showing a modified arrangement.

Referring particularly to Figures 1 and 2, the still 1 is a horizontally arranged cylindrical boiler type of still such as is com-

monly used in the cracking of oil. It is arranged in a suitable furnace setting so that it is heated either by direct heat or by products of combustion in chamber 2. The still is provided with a suitable oil supply pipe 3 thru which a regulated supply of oil can be introduced either in the form of successive charges or in a more or less continuous manner. The oil supply may be automatically regulated in any suitable manner to maintain a constant level in the still. The residue outlet from the still is indicated at 5. The still has a dephlegmating column 26 leading to the vapor pipe and condenser.

Two longitudinal baffles 15 and 16 are provided. These baffles are symmetrically arranged and spaced apart from each other and from the still walls to permit circulation of oil between the baffles and the still walls and between the baffles themselves. These baffles are extended to a considerable height in the still, preferably to a height not greatly below the normal oil level in the still, so that the oil will be caused to circulate from the upper portion thereof between the baffles, and between the baffles and the still walls, and so that the entire body of oil will thus be kept in effective agitation and circulation.

Two longitudinally arranged and perforated gas inlet pipes 17 and 18 are provided having a gas supply main 19 with controlling valve 20 therein, and these perforated pipes are arranged in the spaces forming flues between the baffles 15 and 16 and the still wall so that they discharge the gases upwardly into these respective spaces or flues and cause upward flow of oil therethrough. The arrangement of the perforated pipes 17 and 18 is such that they discharge gaseous currents into the oil between the baffles and the still walls thus decreasing the weight of the body or column of oil between the baffles and the still walls and causing upward flow of this body of oil. The gas thus introduced acts on the "air-lift" principle, causing upward circulation of the oil between the baffles and the still walls and downward circulation of the oil in the spaces between the baffles.

The oil is discharged into the main body of the oil near the upper portion thereof, and oil will be withdrawn from this main body between the inner edges of the two baffles. The flow of the oil will thus be a cyclic flow, from the central portion of the main body of oil thru the spaces between the baffles and the still walls in the opposite direction and back to the central portion of the body of oil. The heating effect is applied mainly to the oil while it is passing upwardly in the spaces between the baffles and the still walls. The "air lift" effect of the injected gases and the thermosiphonic effect of the

application of heat combine to permit rapid circulation between the baffles and the still walls, from the center and bottom outward and upward in opposite direction. The rapid circulation of oil thereby brought about in opposite directions on the two opposite sides of the still will have a sufficient velocity to prevent or remove objectionable "carbon" deposit, thus keeping the still walls substantially free from such deposits and promoting the efficiency of the still as a whole.

The heated oil discharged into the main body of oil near its upper surface will be drawn inwardly by the cyclic circulation and will blend with the remainder of the body of oil, thus bringing the entire body of oil to a practically uniform temperature. The general direction of the paths of the oil during the circulation is indicated by arrows, but it will be understood that the entire body of oil in the central portion of the still will be kept sufficiently agitated and circulated so that it will all be at approximately the same temperature. It will be readily apparent that pipes 17 and 18 might be so arranged or might be replaced by a single pipe, whereby the gases discharged are directed upward thru the aperture between the two baffles 15 and 16. In this case, the injected gases would likewise act on the "air lift" effect to set up an active circulation thru the body of oil and between the baffles and the still walls over the heated surfaces.

In the apparatus illustrated in Figure 3, the same parts are designated by the same reference characters employed in Figures 1 and 2 with a prime appended. The gas supply main 19' is connected to a longitudinally arranged gas inlet pipe 7 arranged to discharge upwardly through the space between the baffles 15' and 16'. The gases are thus discharged upwardly between the baffles and cause a downward flow of oil between the baffles and the still walls.

The gas which is used for bringing about the circulation and stirring of the oil may with advantage be the fixed gas formed during the cracking operation, after the condensable constituents have been removed therefrom in the condenser, but other appropriate gas can be used, such as natural gas or casing head gas, or other gaseous material, such as steam, which has no objectionable effect upon the cracking operation. This fixed gas may be drawn off at the still pressure, where the condenser is maintained under the same pressure as the still, as in the preferred practice, or at a lower pressure, where the condenser is maintained at a lower pressure; and it can then be passed thru a compressor or gas booster for increasing its pressure sufficiently to force it into the still at the desired rate and under

the appropriate pressure. Instead of using the fixed gases after condensable constituents have been separated therefrom, a part of the mixed vapors and gases can be drawn off from the vapor line at substantially the still temperature and pressure and recirculated, thus taking advantage of the temperature of these gases as well as their pressure.

The introduction of the gas currents not only serves to insure effective agitation and circulation of the oil, in the manner above described, but it promotes the regular removal of the lower boiling constituents resulting from the cracking operation, as they are formed, and prevents their remaining in the still for long periods of time to undergo objectionable decomposition. The excess gas, resulting from the cracking operation and from that introduced, can be discharged from the still in any of the usual ways, or a part reused for reintroduction into the still and the excess discharged from the still or condenser.

In carrying out the process, the oil will be continuously circulated and continuously heated in such a way that the temperature of the body of oil as a whole will be maintained at a generally uniform temperature, with avoidance of objectionable local overheating of the oil next to the still wall, and the temperature of the oil will thus be raised into that range of temperatures most favorable to the cracking operation with the production of considerable naphtha and gasoline and relatively little gas and carbon, and without objectionable local overheating of the oil to the still higher temperatures at which much gas and "carbon" are formed. This uniformity of temperature of the oil body as a whole is brought about by the continuous and effective circulation of the entire body of oil, with resulting increased uniformity of the cracking operation, while the oil that is heated by its circulation between the baffles and the still walls is continuously removed so that the formation of a "dead layer" of oil is prevented, with resulting prevention of the heating of such a layer to objectionably high temperature.

It is one advantage of the invention that it brings about an effective circulation of the oil without the use of moving mechanism and therefore without the use of stuffing boxes, so that all connections of the still may be welded and made gas-tight.

Inasmuch as the accumulation of carbon on the still walls is prevented or minimized, the cracking operation can be continued for relatively long periods of time, the oil being supplied continuously thru the oil inlet pipe and the residue being removed continuously or periodically thru the residue outlet pipe. When a considerable accumulation of "carbon" in suspension in the oil has been brought about, the entire body of residue

can be removed and a fresh charge introduced without the necessity of opening the still to clean it of carbon deposit.

It will be understood that the stills are provided with suitable pressure, temperature and level indicating devices as well as with means for producing and maintaining within the still the necessary temperature and pressure conditions for the cracking operation. The cracking operation may thus be carried out under the regulated pressure, for example, of between 60 and 500 lbs. per square inch, and preferably in the neighborhood of 75 to 150 lbs. per square inch, depending upon the nature of the oil to be cracked and the products desired. The prevention of objectionable "carbon" deposit on the heated still walls prevents weakening of the walls by overheating, such as results when the bottom wall of the still becomes incrusted with a thick layer of "carbon" deposit or coke.

Owing to the continuous circulation and substantially uniform temperature of the entire oil body, the cracking operation is improved, with high yields of gasoline and lower gas and coke losses, and hence increased capacity or improved yields for a given sized still, while the effective life of the still is at the same time very materially increased.

The oil feed to the still may be preheated to a greater or less extent before it enters the still. The preheating of the oil can advantageously be carried to such a degree as to vaporize and remove any water present therein before the oil enters the still.

In the accompanying drawings, we have omitted the heat insulation or lagging of the still, connecting pipes, etc., but it will be understood that, in practice, suitable heat insulation will be provided to avoid objectionable losses from all exposed parts of the still and of the system which become heated.

From the foregoing description it will be seen that the improved method and apparatus of the present invention, enable the cracking operation to be carried out in an improved and advantageous manner, with effective agitation and circulation of the entire body of oil in the still, and with resulting uniformity of temperature and of cracking, as well as with effective circulation of the oil over the heated bottom of the still and the prevention of the formation of a "dead layer" of oil and objectionable "carbon" deposit on the heated still walls, this circulation of the oil being effected between longitudinally arranged baffles and between such baffles and the still walls, in a cyclic manner, so that the oil is caused to flow upwardly or downwardly along the side walls of the still, in opposite directions, either toward or away from the center of the still at the bottom, while the entire body of

oil is kept in circulation around the baffles in such a way that all parts of the oil are effectively agitated and circulated.

In referring to the cracking of "oil" in the present specification and claims, we intend to include the treatment of various hydro-carbon oils, and more particularly the treatment of higher boiling fractions and residual oils of petroleum or shale oil distillation, for the production of motor fuel or gasoline; but other oils, such as lignite or coal tar, or tar oils, etc., can be similarly treated; and we include all such materials within the term "oil," as used in the accompanying claims.

It is to be understood that a plurality of stills of the designs disclosed in this specification may be arranged in series and the oil to be cracked passed thru them consecutively.

20 We claim:—

1. In a method of cracking oils in a horizontally arranged drum still, heated by external heat over its lower surface, the step which comprises preventing deposition of carbon in the bottom of the still and stagnation of oil within the still by causing circulation of the entire body of the oil by injecting a gaseous current into a flue within the still and at a point within the flue itself.

2. In a method of cracking oils in a horizontally arranged drum still, heated by external heat over its lower surface, the step which comprises preventing deposition of carbon in the bottom of the still and stagnation of oil within the still by causing circulation of the entire body of the oil by injecting a gaseous current into a flue within the still and at a point within the flue and adjacent the lower extremity thereof.

3. An apparatus for cracking oils comprising a horizontally arranged drum still, means for heating said still externally, means for preventing deposition of carbon in the bottom of the still and stagnation of oil within the still consisting of baffles spaced from each other which, with the wall of the still, form flues, and means for intro-

ducing a gaseous current into each flue at points within the limits of the flues. 50

4. An apparatus for cracking oils comprising a horizontally arranged drum still, means for heating said still externally, means for preventing deposition of carbon in the bottom of the still and stagnation of oil within the still consisting of baffles spaced apart and in spaced relation to the lower portion of the wall of the still, and means for introducing gaseous currents into the spaces between the baffles and the wall 60 at a point between the extremities of the upper and lower edges of each baffle.

5. An apparatus for cracking oils comprising a horizontally arranged drum still, means for heating said still externally, 65 means for preventing deposition of carbon in the bottom of the still and stagnation of oil within the still consisting of longitudinal baffles in said still spaced apart and in spaced relation to the lower portion of the wall of the still, providing confined circulating paths over said lower portion of the wall, and means for introducing gaseous currents into the spaces between the baffles and the wall 75 at points within the spaces and near the lower edge of each baffle.

6. An apparatus for cracking oils comprising a horizontally arranged drum still, means for heating said still externally, means for preventing deposition of carbon 80 in the bottom of the still and stagnation of oil within the still consisting of longitudinal baffles in said still spaced apart and in spaced relation to the lower portion of the wall of said still, providing a confined circulating 85 path over said lower portion of the wall and means for introducing a plurality of gaseous currents within the limits of the confined circulating path for effecting circulation of the oil cyclically from the central portion of the still over said path.

In testimony whereof we affix our signatures.
